DRAWING FRAME WITH ADJUSTABLE HOLDER FOR THE PRESSURE ROLLERS

Ernst Toenniessen, Munich, Germany; vested in the Alien Property Custodian

Application September 23, 1940, Serial No. 358,023
In Germany November 24, 1939

5 Claims. (Cl. 19—134)

The invention relates to a drawing frame for textile rovings and spinning machines, which is provided with a number of pairs of rollers, acting alone or in cooperation with endless belts.

One object of the invention is to simplify adjustment of the drawing frame and to provide an improved apparatus comprising a transverse bar which extends throughout the entire drawing frame in the direction of the roller axes, said bar and the displaceable element of the holder for the pressure rollers being provided with cooperating means for fixing the position of the displaceable elements of the holders.

Another object of the invention is to provide an improved apparatus wherein the elements of the holder for the pressure rollers can easily be disposed and adjusted without loosening clamping means and use of gauges.

A further object of the present invention is to provide an improved apparatus, wherein the holder for the pressure rollers is hinged in open bearings, allowing the radial removal of the holder from its bearing, but wherein the holder at the same time is secured against radial displacement when in the operative position, thus preventing mis-alignment of neighbored rollers in the direction of their axes.

A further object of the invention is to construct the holder for the pressure rollers in such a manner that the clamping means for displaceable elements of the support for the lower rollers, are accessible from above without previous lifting or removal of the holder, thus equally facilitating the adjusting of the drawing frame.

Several embodiments of the drawing frame according to the invention are shown by way of example in the accompanying drawing, in which

Fig. 1 shows in side elevation a drawing frame with section through the bearing bolt of the holder for the pressure rollers on line I—I of Fig. 2.

Fig. 2 shows the holder for the pressure rollers alone viewed from above, the bearing point being shown in cross-section on line II—II of Fig. 1.

Figs. 3, 4 and 5 show in side elevation modified forms of construction of the bearing point of the holder for the pressure rollers.

On the drawing frame shown in Fig. 1 a pair of drawing rolls is designated by 1—I, a pair of middle rollers by 2—II, and a pair of feed rollers by 3—III. The lower rollers II, III are mounted in a slide 4, which is adjustable on the stationary upright frame 5 so that its distance relative to the lower drawing roller I may be adjusted. The pressure rollers 1, 2, 3 are journaled in usual manner on the lateral cutout portions of a holder of the pressure rollers which is composed of two parts 6 and 7. These two parts of the holder for the pressure rollers are mounted one on the other and are freely shiftable in their longitudinal direction, the front part 7 of the holder for the

pressure rollers being guided at its rear end in the front end of part 6. The movement of the two parts in longitudinal direction is limited by a pin 8 fixed in part 6 and projecting through a longitudinal slot 9 in the other part 7. A brake spring 10 is further sunk in the part 6, the head 11 of this spring pressing against the part 7 and ensuring a sufficient braking of the two parts.

A reversing bar 12 is mounted between the lower rollers I, II on the stationary upright frame 5 and has a heart-shaped cross-section and forms the front bearing for a belt 13 which extends from the reversing bar 12 downwards over a stretching means 14 and thence upwards over the middle lower roller II. On the front part 7 of the holder of the pressure rollers a passage element 15 is further mounted above the reversing bar 12. An abutment pin 16 is fixed in the upright frame 5 and projects through the reversing bar 12 so that its upper end engages in a notch 17 formed on the front part 7 of the holder of the pressure rollers. This part has further a scale 18 on its top.

The rear end 19 of the holder of the pressure rollers is hinged on the slide 4 in a bearing 20 constructed as a forked head. The hinge bolt 21 of the bearing is rigidly connected with the holder of the pressure rollers, and on the rear end 19 of part 6 a clamping slit 22 and a clamping screw 23 are provided which effect clamping of the hinge bolt 21. The counter-bearing 20 has on each of its cheeks engaging over the holder of pressure rollers a horizontal slot 24, whereas the hinge bolt 21 within the range of these cheeks of the counter-bearing 20 has notches 25 which are of a depth so that the cross-section of the hinge bolt on line I—I of Fig. 2 remaining between them fits into the slot 24. If therefore the holder 6, 7 of the pressure rollers is swung from the position shown in Fig. 1 in a clockwise direction of 90° in an upward direction, the holder together with the bolt 21 mounted on it can be pulled out of the bearing 20, unless the holder of the pressure rollers strikes with its rear end face in the swung out position against an abutment face 26 of the slide 4.

The slide 4 is clamped by means of a clamping screw 27 on the upright frame 5, the screw extending through the body of the slide and is screwed at its lower end into a nut 28 engaging over the upright frame 5. The rear part 6 of the holder of the pressure rollers has a bore 29 so that it is possible to grip the head of the clamping screw 27, without lifting the holder 55 of the pressure rollers, by a wrench, socket-wrench or the like.

If the drawing frame requires adjustment, it is merely necessary to loosen with the aid of a socket wrench the clamping screw 27 and to then shift, while observing the scale 18, the

slide 4 and the part of the holder of the pressure rollers mounted on the slide in a forward or rearward direction until the desired distance between the pair of middle rollers 2-II and the pair of drawing rollers 1-I is had. During this adjusting the front part 7 of the holder of the pressure rollers remains permanently in its position secured by the abutment pin 16. If the drawing frame is situated very high or if for other reasons the scale 18 cannot be well observed in the working position of the holder of the pressure rollers, the adjusting of the parts may be carried out so that first the holder of the pressure rollers is raised and lifted out of its bearing, the correct adjusting being then effected with the aid of the scale 18, whereupon the holder of the pressure rollers is inserted again into its bearing and the slide 4, which has previously been loosened, together with the holder of the pressure rollers is shifted forward or backward until the notch 17 of the holder of the pressure rollers engages over the abutment pin 16. After tightening of the clamping screw 21 the elements are in the correctly adjusted position.

In the form of construction shown in Fig. 3 the slots 30 in the side cheeks of the counter-bearing 20 mounted in the slide 4 are open at the top, whereas the bolt 31 at the rear end of the holder 32 of the pressure rollers is tightened by means of the clamping screw 33 so securely that the bolt cross-section fitting the slots 30 is in horizontal position when the holder of the pressure rollers is in the operative position. Also in this arrangement the parts can be separated the one from the other after the holder of the pressure rollers has been turned by 90°, it being merely necessary to lift the holder of the pressure rollers in an upward direction.

In the form of construction shown in Fig. 4 the slots 34 of the counter-bearing 20 are of a width equal to the thickness of bolt 35, the bolt being tightened at the end 36 of the holder of the pressure rollers by means of the clamping screw 37. The bolt is held in position by a spring 38 which, when the holder of the pressure rollers is lifted, is forced out of its locking position.

In the form of construction shown in Fig. 5 it is assumed that the bolt 39 has to remain permanently rigidly connected with the counter-bearing of the holder 42 of the pressure rollers. The bolt 39 has transverse notches 40 according to the whole width of the holder of the pressure rollers, whereas the holder of the pressure rollers has at its lower end a slot 41 adapted to the remaining cross-section of the bolt, so that the parts can be separated the one from the other after the holder of the pressure rollers has been turned by 90°.

According to the number of the units lying side by side in a drawing frame, two or more holders of pressure rollers can be clamped on a common bearing axle so that several holders can simultaneously be removed from their bearing points and reinserted. Holders of pressure rollers arranged side by side can also be mounted, in the solid construction shown in Fig. 5, on a common solid axle. So far as no under-frame is coordinated to the juxtaposed units, the holders can be supported at their front end directly on the reversing bar 12 or on the lower feed roller I by a fork-shaped head open in a downward direction and secured against shifting.

The invention is not restricted to the details of the constructions described.

I claim:

1. A drawing frame for textile rovings, comprising in combination, a plurality of pairs of rollers, each pair comprising an upper and a lower roller, a support carrying said lower rollers, a holder having hinge connection with said support and carrying said upper rollers, said holder comprising two mutually shiftable parts, and brake means in one of the parts and acting with pressure against the other part.
2. A drawing frame for textile rovings, comprising in combination a plurality of pairs of rollers, each pair comprising an upper and a lower roller, a support carrying said lower rollers, and comprising a stationary part and a slide displaceable thereon, a holder having hinge connection with said support and carrying said upper rollers, said holder comprising two mutually shiftable parts, brake means in one of the parts and acting with pressure against the other part, and a scale directly disposed on the surface of said one holder part for indicating the distance between neighbored pairs of rollers.
3. A drawing frame for textile rovings, comprising in combination, a plurality of pairs of rollers, each pair comprising an upper and a lower roller, a pair of supports for positioning said lower rollers, each of said supports comprising a stationary part and a slide displaceable thereon, a plurality of holders for positioning said upper rollers, said holders being distant one from another whereby only two thereof cooperate with said supports, and comprising two mutually shiftable parts, a transverse bar in said supports extending throughout the drawing frame in the direction of the roller axes, and cooperating means on said transverse bar and said holders for fixing the position of the displaceable holder parts relative to said transverse bar for the holders which are not cooperating with said supports.
4. A drawing frame for textile rovings, comprising in combination, a plurality of pairs of rollers, each pair comprising an upper and a lower roller, a support carrying said lower rollers, a holder having hinge connection with said support and carrying said upper rollers, one of the bearing parts of said hinge connection having a horizontal cylindrical bore, the other bearing part of said hinge connection having a hinge pin received in said bore, said bore having a circumferential radial slit the width of which is less than the diameter of said bore, said hinge pin having depressions on its circumference for adapting the width of the remaining section of the hinge pin to the width of said radial slit, the latter affording passage to the hinge pin when the holder is in operative position.
5. A drawing frame for textile rovings, comprising in combination a plurality of pairs of rollers, each pair comprising an upper and a lower roller, a support for positioning said lower rollers comprising a stationary part and a slide displaceable thereon, a screw extending from above and throughout the slide, clamping means cooperating with the lower end of said screw, and secured on said support and against rotation and forming a screw nut, and a holder having hinge connection with said support and carrying said upper rollers, and having a vertical bore aligned with said screw for the reception of means for turning the screw.

ERNST TOENIESSEN.
